UNITED STATES PATENT OFFICE.

WILLIAM J. HUNTER, OF NEW YORK, N. Y.

TERMINAL CONNECTER.

Application filed January 19, 1923. Serial No. 613,788.

To all whom it may concern:

Be it known that I, WILLIAM J. HUNTER, a citizen of the United States, and resident of New York, in the county of New York and State of New York, have invented certain new and useful Improvement in Terminal Connecters, of which the following is a specification.

My invention relates to terminal connectors, and the object is to produce a device of simple and efficient construction and operation for securing a cable or an insulated electric conductor to the terminal clip without the use of heat melting means.

Another object is to provide the terminal connector with an electrical intensifier.

With these and other objects in view my invention comprises novel features of construction and combinations of parts which will be hereinafter described and claimed.

Referring to the drawing:

Figure 1 is a side view of a terminal connector embodying my invention, showing the device as connecting a cable or an insulated electrical conductor to a spark plug terminal of an internal combustion engine.

Figure 2 is a top view of the connector and adjuncts;

Figure 3 is an enlarged sectional view on line α α Fig. 2;

Figure 4 is an enlarged horizontal sectional view of the terminal.

Figure 5 is a detached end view of the clip;

Figure 6 is a detached end view of the cable ferrule, or thimble;

Figure 7 is a rear view of the cable thimble or ferrule; and

Figure 8 is a detached side view of the cable thimble or cap showing the dished or convex end.

Numeral 2 represents the terminal clip, made of spring metal, and formed into two arms 3 and 4, intended to grip around the stem 5 of a spark plug. The inner surface of each arm 3 and 4 is threaded at 7 (see Fig. 3) to co-act with the threads 6 of the stem 5, for the purpose of preventing the clip, when on the stem, from accidental displacement therefrom.

To place the clip on the stem, simply pass same through the clip, and pull it inward from same, which will cause the stem to force open the arms and allow them to clasp automatically around the threaded stem.

To remove the clip, simply reverse the action, or tilt it upward.

The clip comprises a bifurcate extension of one end of a tubular or ferrule portion 8, which can be divided at 40 to increase 60 its yielding condition, or it can be made whole. To close or shut off the interior of the ferrule 8, of clip, for preventing oil or other foreign matter entering the same to affect the conductor or cable wires, I 65 form out of the clip metal, at 30, a disk-shaped division piece 10 (see Figs. 4 and 5) bent upwards against the opening of ferrule 8, see Fig. 4.

The end of the ferrule 8 remote from the 70 clip, at 12, is formed with an annular shoulder 14, its object to be described hereafter.

Numeral 15 is the cable, with the electric wires 16 and outside insulation 17.

20 is a tubular member or cap adapted 75 to fit over the end of the cable 15, and having a closed outer end 18. In order to intensify the current passing through wires 16, I provide the closed end 18 of the cap with a covex or cup-shaped formation 26, which 80 provides a spark gap between the extremity of the conductor and the opposing end portion 26, it being noted that the inner peripheral part of the latter affords a seat or stop for the insulation 17 so as to ensure a definite gap effective to intensify the current (see Figs. 4 and 8). The outer end 24 of the cap is made bell-shaped (see Fig. 8) caused by the openings 28 cut in the cap and extending a certain distance along same 85 (see Fig. 8), forming thereby diverging members extending from the open end of the cylindrical thimble 24, and the outer ends thereof each having inwardly projecting prongs or teeth 22 (Figs. 4 and 7) 90 adapted to pierce the insulation 17 of the cable 15.

The cap 20 is first placed over the end of the cable (see Fig. 4). Then the ferrule portion 8 of the clip is passed over and forced along the cap 20 till the convex or cupped end portions 26 abuts against the end closure 10 of the ferrule portion 8 (see Fig. 4). When the ferrule is being pressed over the cap it will force down the resilient diverging members 24, and when fully on the latter will forcibly drive down the teeth 22 into the insulation 17 and effect a lock of the cable and the cap. But to create a double lock, I cause the annular shoulder 14 of clip to auto- 110

2

matically spring down behind the free inner extremities of the members 24 (see Fig. 4) thus locking all the parts firmly together.

5 From the foregoing it will be seen that my device consists of two telescopic units, one of which can be readily applied to the insulated electric conductor and the other then slid on the first, their relative constructions being such that when they are thus associated they are effectually locked together and to the conductor; that is to say the outer element is a simple tubular member internally flanged at its inner end, and having 10 its outer end sealed against ingress of foreign matter and also provided with a bifurcate extension which constitutes resilient gripping arms for detachable engagement with an electrical terminal; and the inner 15 element is a simple tubular member closed by a convex head at its outer end and having its walls peripherally cut to provide resilient diverging arms terminating in teeth which lie adjacent the insulation of the conductor when the element is applied to the end 20 of the latter. Hence when the outer element is slid upon the inner element the diverging arms are pressed inward and their teeth forced into locking relation with the 25 insulation. At the same time the internally flanged end of the outer member engages behind the extremities of the arms and is thus interlocked with the inner member. The inner peripheral portion of the outwardly 30 projecting convex head of the inner element presents a seat or stop to the end of the insulation and thus spaces the inner portion of the head from the conductor to provide a definite spark gap effective to intensify the current, as previously mentioned.

40 What I claim is:

1. A terminal connector comprising two relatively slidable telescopic elements, whereof the inner element consists of a tubular portion having resilient securing members and being adapted to receive one end of an insulated electric conductor, and whereof the outer element consists of a tubular member movable along the inner tubular portion 45 to force the gripping members into locking relation with the insulation of the conductor, the outer end of said outer tubular member being closed by a sealing member and having a bifurcate extension constituting resilient gripper arms for detachable connection with an electrical terminal, said sealing member comprising a discal piece partially cut from the material of the outer element and bent inwardly between and at the 50 roots of the arms.

2. A terminal connector comprising two relatively slidable telescopic elements, whereof the inner element consists of a tubular portion having a closed outer end and resilient securing members remote from said 55 60

end, said tubular portion being adapted to receive one end of an insulated electric conductor, and whereof the outer element consists of a tubular member movable along the inner tubular member to force the securing 70 members into locking relation with the insulation of the conductor, the outer end of said outer tubular member being closed by a sealing member and having a bifurcate extension constituting resilient gripper arms 75 for detachable connection with an electrical terminal.

3. A terminal connector comprising two relatively slidable telescopic elements, whereof the inner element consists of a tubular portion having a closed outer end and having resilient securing members remote from said closed end, said tubular portion being adapted to receive one end of an insulated electric conductor which is spaced from the 85 closed end of the tubular portion to provide a spark gap, and whereof the outer element consists of a tubular member movable along the inner tubular portion to force the securing members into locking relation with the 90 insulation of the conductor, the outer end of said outer tubular member having means for detachable connection with an electrical terminal.

4. A terminal conductor comprising two relatively slidable telescopic elements, whereof the inner element consists of a tubular portion having an outwardly projecting convex head at its outer end and having resilient securing members remote from said head, said tubular portion being adapted to receive one end of an insulated electric conductor and the inner peripheral portion of the head presenting a seat to the insulation and thus spacing the inner portion of the head from the conductor to provide a definite spark gap, and whereof the outer element consists of a tubular member movable along the inner tubular portion to force the securing members into locking relation with the insulation of the conductor, the outer end of said outer tubular member having means for detachable connection with an electrical terminal.

5. A terminal connector comprising two relatively slidable telescopic elements, whereof the inner element consists of a tubular portion having a closed outer end and resilient securing members remote from said end, said tubular portion being adapted to receive one end of an insulated electric conductor, and whereof the outer element consists of a tubular member closed at its outer end by a sealing member and movable along the inner tubular portion to force the securing members into locking relation with the insulation of the conductor, the closed outer end of said outer member having means for detachable connection with an electrical terminal.

6. A terminal connector comprising two relatively slidable telescopic elements, whereof the inner element consists of a tubular portion having resilient securing members and being adapted to receive one end of an insulated electric conductor, and whereof the outer element consists of a tubular member movable along the inner tubular portion to force the securing members into locking relation with the insulation of the conductor, said outer tubular member having at its inner end an internal projection arranged to engage behind the adjacent end of the inner member when the elements are assembled, and having at its outer end projecting gripper arms for detachable engagement with an electrical terminal.
7. A terminal connector comprising two relatively slidable telescopic elements, whereof the inner element consists of a tubular portion having resilient securing members and being adapted to receive one end of an insulated electric conductor, and whereof the outer element consists of a tubular member movable along the inner tubular portion to force the securing members into locking relation with the insulation of the conductor, said outer member having at
- its inner end an internal annular shoulder which engages the extremities of the securing members when the elements are assembled, and having at its outer end projecting gripper arms for detachable connection with an electrical terminal.
8. A terminal connector comprising two relatively slidable telescopic elements, whereof the inner element consists of a tubular portion having resilient diverging arms provided with inwardly projecting teeth and adapted to receive one end of an insulated electric conductor, and whereof the outer element consists of a tubular member movable along the inner tubular portion to force the toothed arms into locking engagement with the insulation of the conductor, said outer member having at its inner end an internal annular shoulder which engages the adjacent ends of the said arms when the elements are assembled, and having at its outer end projecting gripper arms for detachable engagement with an electrical terminal.

Signed at New York, in the county of New York and State of New York this 15 day of April A. D. 1922.

WILLIAM J. HUNTER.
